(57) **CLAIM**

The ornamental design for a luggage arrangement, as shown and described.

DESCRIPTION

FIG. 1 is a front elevational view of a luggage arrangement of the invention showing my new design;

FIG. 2 is a top plan view thereof;

FIG. 3 is a bottom plan view thereof;

FIG. 4 is a one side elevational view thereof (the other side view is a mirror image of FIG. 4); and,

FIG. 5 is a rear elevational view thereof.

The broken lines shown in the drawings are for illustrative purposes only and form no part of the claimed design.

The crisscross pattern of lines in the drawings represent material and is understood to be distributed uniformly over the surface of the luggage arrangement.
